(57) **CLAIM**

The ornamental design for a tracking device charging dock, as shown and described.

DESCRIPTION

FIG. 1 is a perspective view of a tracking device charging dock taken from the top, right, and front;

FIG. 2 is another perspective view of the tracking device charging dock taken from the bottom, back, and left;

FIG. 3 is a front elevation view of the tracking device charging dock of FIG. 1;

FIG. 4 back elevation view of the tracking device charging dock of FIG. 1;

FIG. 5 is a cross-sectional view of the tracking device charging dock, taken along line 5-5 shown in FIG. 8;

FIG. 6 is a right side elevation view of the tracking device charging dock of FIG. 1;

FIG. 7 is a left side elevation view of tracking device charging dock of FIG. 1;

FIG. 8 is a top plan view of the tracking device charging dock of FIG. 1;

FIG. 9 is a cross-sectional view of the tracking device charging dock, taken along line 9-9 shown in FIG. 4; and, FIG. 10 is a bottom plan view of the tracking device charging dock of FIG. 1.

The broken lines shown in the drawings illustrate portions of the tracking device charging dock that form no part of the claimed design.

1 Claim, 7 Drawing Sheets
